CLAIM

The ornamental design for a lid for a food container, as shown and described.

DESCRIPTION

FIG. 1 is a top perspective view of a lid for a food container showing the new design.

FIG. 2 is a bottom perspective view of the lid for a food container of FIG. 1.

FIG. 3 is a front view of the lid for a food container of FIG. 1.

FIG. 4 is a rear view of the lid for a food container of FIG. 1.

FIG. 5 is a right side view of the lid for a food container of FIG. 1.

FIG. 6 is a left side view of the lid for a food container of FIG. 1.

FIG. 7 is a top view of the lid for a food container of FIG. 1; and,

FIG. 8 is a bottom view of the lid for a food container of FIG. 1.

The portions of the drawings depicted in dashed lines form no part of the claimed subject matter.

1 Claim, 6 Drawing Sheets
